[57] CLAIM

The ornamental design for a combined illuminated license plate and frame, as shown and described.

DESCRIPTION

FIG. 1 is a perspective view of a combined illuminated license plate and frame showing our new design, with the cord broken away to indicate indeterminate length, and with the plates shown partly removed from the frame;

FIG. 2 is a front elevational view thereof;

FIG. 3 is a rear elevational view thereof;

FIG. 4 is a left side elevational view thereof, with the opposite side being a mirror image;

FIG. 5 is a top plan view thereof; and,

FIG. 6 is a bottom plan view thereof.

FIG. 1.

FIG. 4.

FIG. 2.

FIG. 6

FIG. 5

FIG. 3
